[57] **CLAIM**

The ornamental design for a pneumatic tire tread and
buttress, as shown and described.

DESCRIPTION

FIG. 1 is a perspective view, partly schematic, of a
pneumatic tire tread and buttress embodying my new
design, it being understood that the pattern is repeated
throughout the circumference of the tread and buttress,
as shown schematically by solid lines, and that the but-
tress pattern is repeated on the opposite side; and,
FIG. 2 is an enlarged, fragmentary development plan
view of the tread and buttress of FIG. 1.

The broken line showing of environmental structure in
FIG. 1 of the drawing is for illustrative purposes only
and forms no part of the claimed design.

FIG. 1

FIG. 2
